UNITED STATES PATENT OFFICE.

HENRY L. KEELER, OF LUNDYS LANE, PENNSYLVANIA.

STATION-INDICATOR.

1,072,955.

Specification of Letters Patent.

Patented Sept. 9, 1913.

Application filed June 5, 1912. Serial No. 701,872.

To all whom it may concern:

Be it known that I, HENRY L. KEELER, a citizen of the United States, residing at Lundy's Lane, in the county of Erie and 5 State of Pennsylvania, have invented certain new and useful Improvements in Station-Indicators; and I do hereby declare the following to be a full, clear, and exact description of the invention, such as will enable others skilled in the art to which it 10 pertains to make and use the same, reference being had to the accompanying drawings, and to the letters of reference marked thereon, forming part of this specification. 15 My invention relates to station indicators for railway or street cars and has for its objects, the construction of certain improvements in that type of station indicators shown and described in Letters-Patent of 20 the United States, No. 867,630, issued to me on the 25th day of June, 1907, and No. 970,717, issued to me September 20, 1910.

The features of my invention will appear hereinafter in the specification and claims, 25 and are illustrated in the accompanying drawings in which:—

Figure 1, is a front view in elevation, of my improved station indicator. Fig. 2, is a 30 vertical section on the line $x-x$ in Fig. 4, looking in the direction of the arrow. Fig. 3, is a section on the line $y-y$, in Fig. 1, showing a plan view of the mechanism of my device. Fig. 4, is a vertical section on the line $z-z$, in Fig. 1, looking in the direction of the arrow.

In these drawings, A, indicates the case of my station indicator, the sides a , thereof being left open. Within this case A, I mount a non-rotatable screw B, the ends b , 40 of which are squared so as to prevent the same from rotating in their fastenings. Adjacent to each end of the screw B, within the case A, I journal pinion-gears C, and upon the threaded portion of the screw B, I place 45 a rotatable nut, D, which engages the threads on the screw, this nut D, being provided with a flange d , having holes d' , therethrough. Passing through the holes d' , in the flange d , of the nut D, are rods E, the 50 ends of which are secured in the pinions C, so that as the pinions C, are rotated, the rods E, will cause the nut D, to rotate on the screw B, and the threads of the screw give longitudinal movement to the nut D. 55 For rotating the pinions C, I provide a spur-gear F, which is secured upon a shaft F',

which extends outward through the case A, of the device.

Mounted upon the shaft F', outside of the case A, is an operating lever G, which is 60 provided with a spring pressed bolt mechanism G', comprising a cylindrical barrel g , having therein a spring g' , against which the bolt G', operates. The barrel g , is provided with a U shaped slot g^2 , in which the 65 bolt-stop g^3 , operates. The bolt G', has an inclined surface on one side thereof, which faces one way as shown in Fig. 1, but when it is desired to reverse the machine, the bolt-stop g^3 , is drawn backward and around 70 through the U-shaped slot g^2 , and when in the lower leg of said slot is released, which will leave the inclined face on the bolt G', on top instead as shown in Fig. 1.

On the shaft F', outside of the operating 75 lever G, is secured a disk H, which is provided with four notches h , adapted to be engaged by the bolt G'. On the outside of the case A, there are lever-stops J, adapted to limit the movement of the lever G, to one 80 quarter of a circle. For moving the lever G, in one direction and retaining it in its normally raised position, I provide a spring mechanism K, which is connected with the lever G, by means of the link l . The spur- 85 gear F, is of such dimension that a one quarter revolution thereof will cause a one half revolution of the pinions C.

Within the case A, on each side of the screw B, I suspend a series of sign cards L, 90 upon rods L', parallel with the screw B, said sign cards being spaced apart on the rods L', by means of washers l , and being secured in proper position, longitudinally, 95 on the rods L', by means of the set screw collars M, thereon.

Secured on the nut D, by means of the screw d^2 , there is an arm N, preferably of circular contour and having in the edge thereof a V-shaped groove n , (see Fig. 3,) 100 said arm N, being adapted to engage the inner edges and upper ends of the name cards L, during its rotation around the screw B, the V shaped groove in the edge thereof embracing the edge of the sign card 105 so that the sign card will not slip off of the edge of the arm N. In the lower part of the case A, are card stops O, adapted to prevent the cards L, from swinging past a vertical line when released by the arm N. 110

In order to call attention to the indicator when a change of card is made, I provide

a bell-mechanism P, of usual, ordinary construction, the operating shaft P', thereof passing inward through the case A, where it is provided with a pinion Q, which inter meshes with one of the pinions C, so that whenever a half rotation is given to the pinions C, the gong-mechanism P, will be sounded.

In operation, when it is desired to change the name card, which projects from the side of the case, as shown in Figs. 1 and 2, the lever G, is pulled downward until it contacts with the lower most stop J, which by means of the bolt G', engaging one of the notches h, in the disk H, imparts a quarter revolution to the spur-gear F, inside of the case A, which in turn causes the pinions C, and nut D, and arm N, to turn one half of a revolution around the screw B; thus releasing a card on one side of the screw and permitting it to swing downward out of sight, the nut D, and arm N, having sufficient longitudinal movement on the screw during its semi-revolution, to reach the proper position opposite the edge of the next succeeding name card on the opposite side of the screw B, and the continued rotation of the nut causing the name card to swing outward as shown in Fig. 2. This operation may be continued as often as desired within the

capacity of the machine, and when it is desired to reverse the operation, the bolt-stop g³, is moved in its slot as hereinbefore described, which will then cause the disk H, to revolve in the opposite direction at each operation of the lever G, so that the nut D, will travel backward over the screw B, to its starting point.

Having thus fully shown and described my invention so as to enable others to construct and use the same, what I claim as new and desire to secure by Letters Patent is:—

In a station indicator the combination of a frame a non-rotatable screw secured in said frame, a nut rotatable on said screw, a series of station cards suspended upon a common pivot at each side of said screw, an arm on said nut adapted to contact successively with the station cards on each side of said screw when said nut is rotated on the screw, and mechanism adapted to cause said nut to rotate on said screw, substantially as set forth.

In testimony whereof I affix my signature, in presence of two witnesses.

HENRY L. KEELER.
